[57] CLAIM

The ornamental design for an electrical terminal, as shown and described.

DESCRIPTION

FIG. 1 is a top plan view of an electrical terminal showing our new design;

FIG. 2 is a side elevational view thereof;

FIG. 3 is a front elevational view thereof;

FIG. 4 is a rear elevational view thereof;

FIG. 5 is an elevational view of the side opposite that shown in FIG. 2;

FIG. 6 is a bottom plan view thereof; and

FIG. 7 is an isometric view of the electrical terminal of FIGS. 1-6.
